[57] CLAIM

The ornamental design for a multiple venturi gasoline-air mixer, as shown and described.

DESCRIPTION

FIG. 1 is a top perspective view of a multiple venturi gasoline-air mixer showing our new design;

FIG. 2 is a bottom perspective view thereof;

FIG. 3 is a top plan view thereof;

FIG. 4 is a bottom plan view thereof;

FIG. 5 is a side elevational view thereof;

FIG. 6 is an end elevational view thereof; and

FIG. 7 is an end elevational view thereof opposite the view shown in FIG. 6.

*Fig. 1.**Fig. 2.**Fig. 4.**Fig. 3.**Fig. 5.**Fig. 6.**Fig. 7.*
